WILLIAM R. MILLS, OF HARTFORD, MICHIGAN.

Letters Patent No. 77,639, dated May 5, 1868.

IMPROVED MOP-WRINGER.

The Schedule referred to in these Letters Patent and making part of the same.

TO WHOM IT MAY CONCERN:

Know all men that I, WILLIAM R. MILLS, of Hartford, in the county of Van Buren, and State of Michigan, have invented a new and useful Improvement in Mop-Wringers; and I do hereby declare that the following is a true and accurate description thereof, reference being had to the accompanying drawings, and to the letters of reference marked thereon, and being a part of this specification.

The object of this invention is to construct an effective and inexpensive apparatus for wringing mops, to prevent the necessity of the operator putting his or her hands into the water for that purpose.

In order to accomplish this end, I place upon the mop-handle, A, a loose sleeve, B, which may be moved up or down the handle, as may be desired, and secured to its position by a set-screw, or any other appropriate or well-known device. Attached to this sleeve by any proper bearings, are the crank and shaft C, provided with bevel-gear wheel D, which meshes into another bevel-gear wheel, E, which is rigidly fastened upon the shaft F, which is journalled into the two supporting-hangers G. The lower end of the shaft F is provided with a suitable head, J, to hold one end of the web H of the mop, while the other end of said web is held by and secured in the head I of the mop-handle.

When a mop is in use, the sleeve is slipped down to the head of the mop; but when it is necessary or desirable to wring the web, the sleeve is slipped up the handle as far as required, when the operator, by turning the crank C, gives motion, by means of the gear-wheels D and E, to the shaft F, the rotary motion of which will effectually wring the web of the mop.

What I claim as my invention, and desire to secure by Letters Patent, is—

The combination of the sleeve B, the crank and shaft C, the bevel-gear wheels D and E, the hangers G, the head J, when arranged with the mop-handle A, the head I, and the web H, when constructed and operating substantially as and for the purpose herein described.

WILLIAM R. MILLS.
